UNITED STATES PATENT OFFICE.

MARTIN BENNETT, OF EUREKA, CALIFORNIA.

HANDLE FOR CROSSCUT-SAWS.

SPECIFICATION forming part of Letters Patent No. 397,580, dated February 12, 1889.

Application filed May 11, 1888. Serial No. 273,587. (No model.)

To all whom it may concern:
Be it known that I, MARTIN BENNETT, a citizen of the United States, residing at Eureka, in the county of Humboldt and State of California, have invented certain new and useful Improvements in Handles for Crosscut-Saws; and I do hereby declare that the following is a full, clear, and exact description of my said invention, reference being had to the drawings that accompany and form part of this specification.

My invention relates to handles for cross-cut-saws; and it consists in certain improvements on the handle patented to me on the 15 3d day of January, 1888, Letters Patent No. 375,916, and which have for their object to produce a more simple construction as well as to provide a handle that readily adjusts itself to any saw-blade, as will be more fully 20 explained hereinafter.

The following description explains the nature of my said improvements and the manner in which I proceed to construct and carry out the same, the accompanying drawings being 25 referred to by figures and letters.

Figure 1 is a side view of my improved handle applied to one end of a saw, a portion of the stock or wood portion of the handle and the end portion of the saw-blade being 30 shown. Fig. 2 is a top view of the clamp-plates, with detail of clamps shown separately. Figs. 3 and 4 are outside and inside views of one of the clamp-plates, showing more particularly the construction and arrangement of the studs or pins that enter and hold the saw-plate. Fig. 5 shows a modification 35 in the construction of the clamp, both jaws having holes or openings for the passage therethrough of a single pin or stud for holding the saw-plate. Fig. 6 shows a modification 40 in the construction of the clamp, whereby it is provided with a single pin or stud for entering and holding the saw-plate, instead of the two pins, as in other figures of the 45 drawings. Fig. 7 is a cross-sectional view on the line *y* of Fig. 3. Fig. 8 is a side view, similar to that in Fig. 1, of the modified construction of the clamp shown in Fig. 6.

Similar letters of reference indicate corresponding parts in all the figures of the drawings.

My present improvement consists in certain

construction and combination of clamps having a socket to take the wooden bar or stock that forms the handle, and two jaws between 55 which the end of the saw-blade is grasped and finally secured by the joint action of studs or pins on the end of the clamps that take through holes in the saw-blade, and a bearing-block held between the two jaws 60 against the end of the saw-blade and secured in position by a clamp, bolt, and nut, the block being set between the jaws, and the bolt working through slots in the clamp, so that the block can be adjusted to the peculiar 65 form or character of saw and always brought up to a close seat and bearing against its end. Adjustment of the studs or pins at the end of the clamps is also provided by a novel construction and arrangement of shifting studs 70 that form, also, a feature of this improvement.

Referring to the drawings, A represents the portion of a saw-blade at one end, and B B^x the two jaws or parts of the clamp between which the saw is placed.

C is the socket for the handle. Said socket C has an inwardly-projecting pin (shown in Fig. 2,) whereby it is more securely attached to the handle.

The two parts B B^x are slotted at *d* to let 80 the clamp-bolt D through the two plates from one side to the other.

E is a bearing-block of suitable thickness to fit into and slide in the space *b*, provided between the two jaws, and furnished, also, 85 with flanges E^x at top and bottom of suitable projection to ride on the edges of the plates. The block E is set in between the two jaws, and the bolt D, passing through the slots *d*, takes through an opening, *e*, in the middle of 90 the block, the head D^x of the bolt having a bearing on the back of one jaw and the nut D² bearing against the back of the opposite jaw.

Figs. 5 and 6 illustrate a modification in 95 the construction of the clamp for connecting it to the saw-blade. As above described, the clamp has been said to be provided with two studs or pins that pass through the saw-blade; but in the modification shown in Fig. 6 the 100 clamp is provided with a single pin, *p*, while in Fig. 5 both jaws have openings or holes through which a pin or stud may pass.

At a point in front of the block E a stud

or pin, *p*, is fixed on the inner face of one jaw, to take through the hole or perforation in the saw-blade, that is generally provided for this purpose. For such fastening means at the present time pins or rivets fixed solidly in the clamp and through the saw-blade are used; but I have found in many instances, when applying my handles to blades of different manufacturers, that the holes provided for these pins and rivets are not always in the same position with reference to the end of the saw-blades, nor always in exact line with each other, so that it becomes difficult sometimes to set and fix the saw-handle in position at right angles with the line of the saw. Therefore, to accommodate different kinds of saw-blades and compensate for any variations in the position of the holes for the studs or rivets, I have produced and make use of the following construction:

At the end of the jaw I form two slots, *g g*, inclined to the longitudinal center line of the clamp and converging toward the saw-engaging end thereof. Through these slots, from the outside, are set pins or studs *H* of suitable length to take into inclined slots or recesses *g' g'*, of similar character and equal inclination, in the opposite jaw. The heads of these pins being enlarged to ride over the back edge of the slots *g'*, they are confined in place by a stop-plate, *I*, that is secured against the back of the jaw, after the pins are placed in the slots, by means of a screw, *k*. Sufficient space under the plate *I* is afforded to allow the studs to slide in their slots; but being thus confined they are kept from dropping out, while having suitable free movement. As

thus set and held, it will be seen that in any variation of the holes in the saw-plate from the vertical line the studs will shift and adjust themselves to take through the holes and will come to a bearing in the opposite jaw. When the block *E* is brought up against the end of the saw and the clamp-screw is tightened, the blade will be firmly clamped and the handle kept in true position under all conditions and directions of strain and forces it is called upon to bear.

The construction shown in Figs. 1 and 2 has the clamp in two halves on separate pieces.

Having thus fully described my invention, what I claim as new, and desire to secure by Letters Patent, is—

1. In a handle for crosscut-saws, the combination of the slotted clamp-plates having sockets at one end, jaws to take the saw-blade at the other end, provided with a stud or studs to take through the saw-blade, and the sliding bearing-block and clamp-screw, arranged, substantially as described, for operation as set forth.

2. In a handle for crosscut-saws, the combination, with the clamp-jaws having the inclined slots or grooves, of the studs or pins movable therein, the bearing-block, and the clamp-screw, all arranged to operate substantially as described.

In testimony that I claim the foregoing I have hereunto set my hand and seal.

MARTIN BENNETT. [L. S.]
